UNITED STATES PATENT OFFICE.

PETER W. MURPHY, OF CHICAGO, ILLINOIS, ASSIGNOR TO MURPHY ENGINEERING COMPANY, OF CHICAGO, ILLINOIS, A CORPORATION OF MICHIGAN.

INTERNAL-COMBUSTION ENGINE.

1,389,967.

Specification of Letters Patent.

Patented Sept. 6, 1921.

Application filed February 10, 1919. Serial No. 276,193.

To all whom it may concern:

Be it known that I, PETER W. MURPHY, a citizen of the United States, residing at Chicago, in the county of Cook and State of Illinois, have invented a certain new and useful Improvement in Internal - Combustion Engines, of which the following is a full, clear, concise, and exact description, reference being had to the accompanying drawings, forming a part of this specification.

My invention relates to internal combustion engines and has to do more particularly with that type of engine in which a series of cylinders and pistons are circularly disposed around the main shaft and in which the pistons reciprocate parallel to the axis of the main shaft. One of the features of my invention is the provision of a cylinder head, carrying intake and exhaust puppet valves for each of the cylinders and in which a valve chamber is provided and so flared out or enlarged that valves of large diameters may be used. Another feature of my invention is that the cylinder head with its enlarged valve chamber is so constructed that the valves, although their total diameter is substantially the same or greater than that of the cylinder, may be readily removed from the cylinder head. Another advantage of my improved construction is that the valves may be disposed with their stems parallel to the main shaft, instead of being at an angle as in former engines, so that clearance between the valve head and the cylinder is reduced to a minimum. Another feature of my invention is the provision of a valve construction in which the valve stems are disposed parallel to the main shaft with tappets disposed perpendicular to the shaft and operated by peripherally faced cams, with rocker arms in the shape of bell-crank levers disposed between the tappets and the valve stems for operating the valve.

For a better understanding of my invention reference is to be had to the accompanying drawings in which—

Figure 1 is a longitudinal section through an internal combustion engine having my invention applied thereto; and

Fig. 2 is an enlarged end view of one end of the engine.

Referring now more particularly to the detail construction of my invention it comprises a hollow main shaft 3 supporting a

cam 4 which is acted upon by a plurality of circularly disposed pistons 5 connected through a piston rod 6 to a slide 7 carrying rollers 8 to act upon opposed faces of the cam 4 to rotate the shaft 3. As shown in Fig. 2 there are ten cylinders for each end of the engine but of course, my invention is not limited to any particular number of cylinders.

A cylinder head is provided carrying intake valves 9 and exhaust valves 10, having their stems disposed parallel to the axis of the main shaft and suitably supported in the cylinder head. In engines of this type it is desirable to have valve heads of comparatively large diameter so that the intake and exhaust may be accomplished with a shorter movement of the valve, or a larger volume of intake or exhaust area provided with a movement of the valves the same as where valves of smaller diameter are used. As shown in the drawing, the total diameter of the valve heads is greater than the diameter of the cylinder. In order to permit the valves to be readily withdrawn and at the same time have their stems parallel to the main shaft, I also provide a chamber 11 of minimum clearance, and preferably split the cylinder head at 12, the part 13 of the cylinder head adjacent to the cylinder being flared out from the cylinder while the chamber in the valve carrying part 14 of the cylinder head is straight so as to permit withdrawal of the valves 9, 10. It will be apparent that although the total diameter of the valve heads is greater than the diameter of the cylinder, by means of my improved construction the valve heads are set in parallel planes and furthermore a valve chamber of minimum clearance is provided at the same time permitting ready removal of the valve.

Now in order to operate the valves I provide operating mechanism which permits of the use of a peripherally faced cam as distinguished from the side faced and more expensive cam heretofore used. In the preferred form I provide an intake cam 15 and exhaust cam 16 suitably fastened to the main shaft 3, the exhaust cam being in lead of the inlet cam as shown in Fig. 2. These cams, 15 and 16, operate upon tappets 17, 18 suitably supported in the cylinder head and carry rollers which are in engagement with the cam surfaces. I also provide in-

termidately disposed rocker arms in the shape of bell-crank levers 19, 20 suitably supported upon the cylinder head and carrying adjusting means in the form of threaded studs 21, 22 adapted for properly positioning the rocker arms relative to the tappets and valve stems.

In the form of engine illustrated herein it is to be understood that there is a series 10 of cylinders and a corresponding cylinder head carried upon each end of the central casing 23, each end being of substantially the same construction.

In the operation of the engine shown herein 15 in the pistons 5, which are oppositely connected to the roller slides 7, act upon the cam 4 to rotate the shaft 3. The rotation of this shaft of course operates the intake and exhaust valves 9 and 10 respectively of the 20 various cylinders by means of the cams 15 and 16 and the intermediately disposed tappets and rocker arms.

An intake 24 is shown leading into the intake manifold 25 which is circularly disposed around the main shaft and connected to the various intake valves 9. Thus as the various valves 9 are operated, gas is drawn into the cylinders and thereafter exhausted out into the atmosphere through the exhaust 30 valves 10 and exhaust opening 26.

What I claim as new and desire to secure by U. S. Letters Patent is:

1. In an internal combustion engine, a main shaft, cylinders and pistons disposed 35 around the shaft and parallel thereto, a cylinder head for said cylinders, intake and exhaust puppet valves parallel with the shaft carried by the cylinder head for each cylinder, peripherally faced cams axially aligned 40 with the main shaft, and rocker arms connecting each of said cams and each set of said valves.

2. In an internal combustion engine, a rotatable main shaft, cylinders and pistons 45 disposed around the shaft and parallel thereto, a cylinder head for said cylinders, intake and exhaust puppet valves carried by the cylinder head for each cylinder and having valve stems substantially parallel to the axis

50 of the main shaft, peripherally faced cams axially aligned with the main shaft, and rocker arms connecting the cams and valves, there being a single cam for all of the intake valves and a single cam for all of the exhaust valves.

3. In an internal combustion engine, a rotatable main shaft, cylinders and pistons disposed around the shaft and parallel thereto, a cylinder head for said cylinders, intake 60 and exhaust puppet valves carried by the cylinder head for each cylinder and having valve stems substantially parallel to the axis of the main shaft, peripherally faced cams

axially aligned with the main shaft, tappets operated by the cams and bell-crank rocker 65 arms connecting each of said cams and each set of said valves.

4. In an internal combustion engine, a main shaft, cylinders and pistons disposed around said shaft and parallel thereto, an intake and an exhaust valve for each cylinder 70 the total diameter of the heads of which is at least substantially that of the piston, a cylinder head supporting said valves with their heads adjacent the corresponding ends of 75 the cylinders, and a split valve chamber for each cylinder enlarged or flared out wider than the outer edges of the valves and split to permit ready withdrawal thereof through the valve chamber. 80

5. In an internal combustion engine, a main shaft, cylinders and pistons disposed around said shaft and parallel thereto, an intake and an exhaust valve for each cylinder 85 the total diameter of the heads of which is at least substantially that of the piston, a cylinder head supporting said valves with their heads adjacent the corresponding end of the cylinder, valve chambers in the cylinder head extending to the outer edge of 90 each pair of valves, and larger than the piston diameter so as to permit removal of the valves, and converging sides extending from said edges of the valve chambers to the edge of the cylinder. 95

6. In an internal combustion engine, a main shaft, a series of cylinders and pistons disposed around the shaft and parallel thereto, an intake and exhaust valve for each cylinder having valve heads setting in the 100 same plane and whose total diameter is greater than that of the piston, each pair of valve-heads being in the same plane parallel to the cylinder end and adjacent thereto, a cylinder head supporting the valves, valve 105 chambers in the cylinder head each extending beyond the outer edges of each pair of valves, and an intermediate member disposed between the cylinder end and cylinder head and having converging walled 110 chambers connecting the cylinder head valve chambers and cylinders.

7. In an internal combustion engine, a rotatable main shaft, cylinders and pistons disposed around the shaft, an outer row of 115 valves disposed around the shaft, an inner row of valves disposed around the shaft, a peripherally faced cam for each row of valves connected with the shaft, and rocker arms each connecting a cam and valve, said 120 cams being mounted on the shaft and rotatable therewith.

In witness whereof, I hereunto subscribe my name this 30th day of September, A. D. 1918.

PETER W. MURPHY.
